VALVE HANDLE

Jacob Podolsky, Dorchester, Mass.

Application May 11, 1932, Serial No. 610,588

6 Claims. (Cl. 287—53)

The present invention relates to stem-turning devices, and more particularly to handles and the like for turning valve stems.

According to present-day practice, the valve handle is fixed to the valve stem in the factory, and the parts are then sold as a unit in the trade. When the handle becomes broken, it becomes necessary either to find a new handle to match the stem, or else to discard both elements and purchase a new combination of handle and stem. The first alternative is attended with difficulties because, the parts not being completely standardized, no one handle that is available in the stores will fit all valve stems; so that it becomes necessary to keep in stock a very large assortment of shapes and sizes. Even when the proper shape and size happens to be in stock, furthermore, it frequently happens that it will not fit the valve stem because of wearing down of the parts. The second alternative, therefore, is more often resorted to. It is, furthermore, frequently desirable to remove the handle from the stem, so as to prevent unauthorized turning of the latter, and this, too, is not convenient with most present-day constructions.

An object of the present invention, therefore, is to provide a new and improved device for turning stems.

A further object is to provide a new and improved device for turning valve stems.

Another object is to provide a single handle or other turning device that shall be readily adapted to the turning of a large number of different valves or other stems.

Still another object is to adapt any of a large number of standardized handles for use with a single stem; or, conversely, any of a large number of stems for use with a single handle.

Other and further objects will be explained hereinafter, it being understood that it is intended, by suitable expression in the claims, to express all the novelty that the invention may possess.

The invention will now be explained in connection with the accompanying drawing, in which Fig. 1 is an elevation of a valve handle embodying the present invention; Fig. 2 is a vertical section taken upon the line 2—2 of Fig. 1, looking in the direction of the arrows; Fig. 3 is a perspective view, showing the parts separated, for clearness; and Figs. 4 to 6 are views of modifications.

A rotary stem 2 is shown provided with a handle 4 for turning the same. This handle may be of the form shown in Figs. 1, 2 and 3, or it may take any other form, such as a soap dish 6, shown in

Fig. 4. The stem 2 is ordinarily provided with a polygonal top 8 adapted to be received in a correspondingly shaped socket or opening 10 provided upon the underside of the handle. It is necessary, therefore, to keep in stock as many different handles with correspondingly shaped sockets 10 as the stems 2 are provided with tops 8.

According to the present invention, however, a single handle 4 or 6 may be utilized in connection with all stems 2 of different sizes in use. To bring about this result, a cubical member 12 is shown in Figs. 1 to 4 provided with a cylindrical or other conventional shaped, oversized socket 14 within which may be received loosely the top 8 of the stem 2. A set screw 16 may be threaded into a threaded opening 18 of the member 12 and against the top 8 of the stem 2. That wall of the socket 14 through which the set screw 16 extends will naturally become spaced from the oppositely disposed wall of the stem 2, except in the rare instances when the stem 2 exactly fits the socket 14. The top 8 is thus received in the socket 14 and becomes fixed to the member 12 by the set screw 16. If the top 8 is non-circular, as shown more particularly in Fig. 3, the parts will be held together very firmly.

Though the socket 14 is shown cylindrical, the effect of this cylindrical form becomes lost by reason of the set screw 16 so that, in effect, the socket 14 and the top 8 of the member 2 are provided with non-circular portions cooperating with each other to hold the parts together. The top 8 is shown in Fig. 3 as of polygonal or cubical form, and the socket 14 may be of corresponding polygonal form, if desired.

The member 12 being of the same polygonal or cubical shape as the socket 10 in the handle 4 or 6, the combination of the handle 4 or 6 and the cube 12 may be used in connection with a very large number of different sizes and shapes of tops 8 for the stem 2. Indeed, the member 12 and the stem 2 may be regarded as in effect a single stem having a constant size and shape of top 8 for cooperating with but a single corresponding size and shape of socket 10 in the handle 4 or 6.

The handle 4 may be secured against accidental displacement from the member 12 by means of a collar 20 loosely mounted upon the stem 2 and having external threads 22 for cooperating with internal threads 24 provided upon the handle 4. In this manner, the polygonal exterior member 12 is detachably held fixed in position in the polygonal interior socket 10 without accidental displacement, the parts cooper-

ating to permit turning of the stem 2 by the handle 4.

The opening 14 may be so designed as to receive a very large number of different sizes and shapes of stem 2, either with one or a plurality of set screws 16. A single member 12 may thus cooperate with a large number of stems 2. If desired, however, a number of separate cubical members 12, such as shown in Fig. 3, may be provided, of different sizes and shapes, and having the same or different sizes and shapes of socket opening 14 in one face thereof. A single cubical member may, on the other hand, as shown in Figs. 5 and 6, have in each face thereof a socket 15 for receiving a stem of a particular shape and size. In this manner, the same cubical member 12 may be adapted to cooperate with six different sizes and shapes of stems. In such case, the sockets in the cubical member 12 may be polygonal, as shown in Fig. 5, cylindrical, as shown in Fig. 6, or of any other desired size and shape. Further modifications will occur to persons skilled in the art and all such are considered to fall within the spirit and scope of the invention as defined in the appended claims.

What is claimed is:

1. A device of the class described for use in association with stems of different sizes and having a cubical member having in each face thereof a socket for receiving one of the stems, and a member having a socket provided with four walls corresponding in shape to four walls of the cubical member for receiving the cubical member, the walls of the cubical member engaging corresponding walls of the second-named member to prevent relative turning movement of the members.
2. A device of the class described for use in association with stems of different sizes and having a member in the form of a parallelopiped having in each face thereof a socket for receiving one of the stems, a member having a socket provided with walls corresponding in shape to the walls of the parallelopiped for receiving the first-named member with the walls of the parallelopiped in engagement with the walls of the socket, means engaging the parallelopiped and the second-named member to hold the parallelopiped in the socket.
3. A handle for use in association with rotary stems of different sizes and having a cubical member having in each face thereof a socket for receiving one of the stems, a handle having a

socket provided with walls corresponding in shape to the four walls of the cubical member for receiving the cubical member with the said four walls of the cubical member in engagement with the said corresponding walls of the socket, means engaging the cubical member and the handle to hold the cubical member in the socket.

4. A device of the class described for use in association with stems of different sizes and having a cubical member having in each face thereof a socket for receiving one of the stems, and a receptacle having a socket provided with walls corresponding in shape to the four walls of the cubical member for receiving the cubical member with the said four walls of the cubical member in engagement with the said corresponding walls of the socket, means engaging the cubical member and the receptacle to hold the cubical member in the socket.

5. A device of the class described for use in association with stems of different sizes comprising a member provided with an oversized socket for receiving the end of any of said stems, the said member being provided with adjustable means for clamping the said end against movement in the socket between the adjustable means and a wall of the socket, a member having a sleeve in which the first-named member is adapted to be received, means for preventing relative rotary movement of the members but permitting their relative movement in a direction longitudinal of the stem, and means for locking the members against relative movement in the said direction longitudinal of the stem.

6. A device of the class described for use in association with stems of different sizes comprising a member provided with a socket for receiving the end of any of the said stems, the said member being provided with adjustable means for clamping the said end against movement in the socket, a handle member having a sleeve in which the first-named member is adapted to be received, the first-named member and the sleeve having cooperating portions for preventing relative rotary movement of the first-named member and the handle member but permitting relative movement of the first-named member and the handle member in a direction longitudinal of the stem, and means for locking the first-named member and the handle member against relative movement in the said direction longitudinal of the stem.

JACOB PODOLSKY.
